(57) **CLAIM**

The ornamental design for a near eye display, as shown and described.

DESCRIPTION

FIG. 1 is a front top right perspective view of a near eye display;

FIG. 2 is a rear left bottom perspective view thereof;

FIG. 3 is a rear right bottom perspective view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a right elevational view thereof; and,

FIG. 9 is a left elevational view thereof.

The broken line showing a pair of arms, a pair of hinges, and a headband in FIGS. 1–9 are included for the purpose of illustrating environmental structure and forms no part of the claimed design.
